UNITED STATES PATENT OFFICE.

FREDERICK F. GAINES, OF SAVANNAH, GEORGIA, ASSIGNOR, BY MESNE ASSIGNMENTS, TO AMERICAN ARCH COMPANY, OF NEW YORK, N. Y., A CORPORATION OF DELAWARE.

LOCOMOTIVE.

1,177,313.

Specification of Letters Patent. Patented Mar. 28, 1916.

Application filed July 24, 1913. Serial No. 780,967.

To all whom it may concern:

Be it known that I, FREDERICK F. GAINES, a citizen of the United States, and a resident of Savannah, Chatham county, Georgia, have invented certain new and useful improvements in Locomotives, of which the following is a specification.

My invention relates to improvements in locomotive boilers and has particular reference to boilers of the wide firebox type.

In the modern development of locomotives it has been found necessary to make the firebox as wide as practical in order to provide sufficient grate area, and in conjunction with the large driving wheels now used this has forced the raising of the grate to a height where the forward end of the mudring will clear the large rear drivers of the locomotive. As the total height is limited, this raising of the grate has tended to reduce the height of the firebox itself to such an extent that proper combustion cannot be maintained therein. These detrimental features are made particularly noticeable when it is desired to equip such fireboxes with a transverse baffle wall arranged between the fuel bed and flues.

The object of my invention is to provide a firebox construction in which and by which the advantages of the wide firebox shall be preserved and by means of which the advantages of the transverse refractory baffle may be combined with the wide grate in such a manner that the combustion of the fuel used shall be substantially perfect and complete within the firebox, the heat thereof most advantageously transmitted to the water of the boiler and the ejection of unburned fuel particles and other non-gaseous products of combustion from the firebox shall be effectively prevented.

A further object of my invention is to provide a firebox of the wide type which shall be adapted to receive a cross wall therein and which shall be so constructed that a wall of suitable height may be installed without reducing the passage above the wall to too small an area.

A further object of my invention is to increase the net quantity of the fuel which can be advantageously burned in a firebox of specified dimensions; to increase the economy and efficiency of fireboxes; and to prevent the escaping of the fuel or gases of

combustion from the firebox until substantially perfect combustion has taken place.

My invention consists in a locomotive boiler firebox wherein the side walls between their ends drop below the general level of the lower edge of the firebox, the lowest point being adjacent to the forward end and spaced from the flue sheet, and a refractory cross wall in the firebox arranged opposite to or between these lower points and rising within the firebox.

My invention also consists in a locomotive equipped with a wide firebox, the forward end thereof being arranged above the rear drivers of the locomotive, the rear end of the firebox being arranged at substantially the same level as the forward end and the sides being inclined downwardly from each end to a point substantially a quarter of the length of the firebox from the forward end and a transverse refractory baffle or wall arranged within the firebox between the low points of the side walls thereof, a grate extending upwardly from the lower part of the wall to the rear end of the fire box and a floor closing the space between the cross wall and the forward end of the firebox.

It has also been difficult heretofore in fireboxes of this type, wherein the grate extends to the forward end of the boiler, to obtain the benefits of water circulating tubes which extend from the lower part of the flue sheet to the upper part of the rear sheet, for the reason that the space between the lower flues and the grate surface at the forward end of the boiler has been too shallow to permit the installation of such tubes, above a fuel bed of the proper thickness. Furthermore, as these boxes are relatively very wide and as the water circulating tubes could not be installed therein, it has been difficult, if not absolutely impossible, to install or make use of so-called "front arches" which are being used at the present time in locomotive boiler fireboxes to enhance the efficiency thereof. These difficulties are eliminated by my invention for I separate the forward end of the firebox from the forward end of the grate by means of a refractory cross wall, and, furthermore, I depress the forward end of the grate to permit a wall of required height to be built in the firebox at this point without encroaching too much upon the passage above the

wall. I am thus enabled to carry the fuel bed on the grates, which extend from the wall to the rear end of the boiler, of the desired depth regardless of the relation of the 5 forward end of the water circulating tubes to the lower edge of the forward wall in the firebox and as I am thus enabled to install water circulating tubes I can combine with the refractory cross wall the advantages of 10 a front arch composed of bricks which rest on and are supported by the tubes.

My invention will be more readily understood by reference to the accompanying drawings forming part of this specification 15 and in which:

Figure 1 is a longitudinal sectional view of the rear portion of a locomotive which embodies my invention; Fig. 2 is a transverse sectional view of the firebox on the line 2—2 of Fig. 1; Fig. 3 is a view similar to Fig. 2, looking forward in the firebox and taken on the line 3—3 of Fig. 1; and Fig. 4 is a section of the firebox similar to Fig. 3, taken on the line 4—4 of Fig. 1.

20 While I have illustrated my invention as embodied in a firebox of the extreme wide type it will be apparent to those skilled in the art that many of the features of the invention may be used in narrower fireboxes 25 with equal advantage.

In the drawings I have illustrated the rear portion only of a locomotive showing a firebox A mounted on the locomotive side frames B, the frames being supported upon 30 the rear trailer wheels C and the large drivers D. The fire box is arranged with its forward end a^1 above the large drivers, and the box is of such a width relative to the transverse spacing of the drivers that the sides a^2 35 of the firebox are considerably beyond the drivers transversely of the firebox. The lower edge a^3 of the forward end of the firebox is raised considerably above the upper edges of the frames in order that sufficient 40 space may be provided between the drivers and this edge, to allow for the relative up and down movement of the boiler, and in order that the boiler, as a whole, may not be raised too high the barrel a^4 of the boiler 45 is arranged as low as possible, thus making the front water leg a^5 relatively short vertically. In boilers of this type, as heretofore used, the grate extended from the lower edge a^6 of the front end of the boiler to the rear 50 end a^6 , and consequently the space between the forward end of the grate and the lowermost of the flues a^7 was too small to permit the carrying of a fuel bed of proper depth and particularly eliminating the possibility 55 of installation and use of arch or water circulating tubes. I eliminate these undesirable features by cutting off the forward part 60 of the firebox a^8 from the rear part a^9 thereof, by means of a refractory cross wall E. 65 I arrange this wall preferably about mid-

way between the middle of the length of the firebox and the forward end, whereby the forward space a^8 is considerably less in dimensions than the main combustion chamber a^9 . Furthermore, I drop the wall down 70 so that its lower edge is below the forward end a^9 of the firebox, thereby producing at this point a firebox of considerably greater vertical depth than at the forward end, that is, the space between the lower edge of the 75 wall and the crown sheet a^{10} is considerably more than the height of the flue sheet. This provides sufficient height at this point so that I can build the wall E of a reasonable height without too greatly reducing the 80 space or passage a^{11} between the upper edge of the wall and the crown sheet. The wall E not only serves to cut off the forward end of the firebox and thus permit the installation of water circulating tubes F but it 85 serves also to prevent the direct flow of the gases from the fuel bed to the flues and serves to effect the intermingling and mixing of the gases of combustion and thus result in their more perfect combustion.

In the form of my invention illustrated in the drawings I have arranged a grate G between the lower edge of the wall E and the rear sheet a^9 of the firebox inclined upwardly from the base of the wall, the rear end of the firebox, as shown, is provided with one or more fuel doors or openings a^{12} . As the grate as described inclines downwardly and forwardly from the rear end of the firebox, the fuel can be readily deposited upon the fuel bed in the required places and, furthermore, the inclination of the grate serves to cause the fuel bed to work forward in the firebox due to the vibration and jarring to which the firebox is subjected in use. The lower edges a^{13} of the sides a^2 conform to and with the position of the cross wall E, that is, the forward parts incline downwardly from the forward end a^9 of the firebox to the lower part of the wall and the rear portions incline upwardly from the wall to the rear end of the firebox. The side sheets thus serving to completely close the sides of the firebox, I preferably form the wall E of a plurality of horizontal rows 115 e^1 of bricks e^2 , and I support the wall upon a cross bearer or bridge member H which extends across the width of the firebox and is secured at its ends to the lower edges of the sides of the firebox. This bridge member is provided with depending bearing portions h^1 spaced in accordance with the spacing of the frames B and adapted to be supported upon suitable bearings thereon. This bridge member is in the form of an open bottomed trough having a forward vertical wall h^2 , a rear vertical wall h^3 and an upper horizontal wall h^4 . The bridge member is co-extensive in width with the thickness of the wall E and its rear wall h^3 rises above 120 125 130

the horizontal plate h^4 and forms an abutment h^5 to assist in retaining the wall E in position on this supporting member. I secure a buck stay plate h^6 to the forward wall 5 h^2 of the supporting member and this plate rises in contact with the forward face of the wall E serving to protect the wall and retain it in position. The bricks e^2 of which the wall is composed are preferably provided on their upper surfaces with centrally arranged projections or tongues e^3 , and on their lower edges with complementary grooves or slots e^4 whereby the several rows 10 of which the wall is composed are interlocked together. As a further security I sometimes fasten the upper row of bricks of which the wall is composed to the upper end of the buck stay plate by means of bolts e^5 . I close the space between the wall and the 15 forward end of the boiler by means of an upwardly and forwardly inclined floor plate K securing it at its rear edge to the bridge member and at its forward edge to the firebox.

20 One advantageous feature of my invention is that the auxiliary combustion chamber a^8 serves to permit the expansion of the gases of combustion as they enter therein and these gases consequently are caused to drop or deposit their burden of cinders or other non-gaseous products of combustion. These products collect in the lower end of this chamber and for the purpose of conveniently removing them, from time to time, I 25 provide a cinder outlet or hopper k^1 in the middle portion of the lower end of this chamber and I normally keep the lower end of this cinder hopper closed by means of a cover plate k^2 . For the purpose of causing 30 the cinders or other particles which may collect in this chamber to collect within the outlet k^1 I fill in the lower end of this chamber with suitable material providing it with a hopped floor k^3 which inclines from the 35 walls thereof to the outlet k^1 .

40 For the purpose of aiding in the thorough and complete combustion of the fuel, I provide the wall E with vertically extending air inlet passages e^6 which extend from the lower edge of the wall and open into the main combustion chamber a^9 through rearwardly extending inlets e^7 which open through the rear face of the wall below the upper edge thereof and for the purpose of admitting air into these passages I provide suitable nozzles e^8 secured in openings e^9 45 in the upper wall h^4 of the bearing member and which project downwardly therefrom having their lower ends extending forwardly and provided with flaring nozzles e^{10} . This construction serves to force air upwardly through the passage e^6 , particularly when the locomotive is in motion forwardly. The water circulating tubes F extend upwardly from the lower part of the flue sheet 50

to the upper part of the rear sheet and serve not only to increase the circulation of the water in the boiler, but these tubes also serve as excellent mediums through which to transmit heat from the firebox to the water. 70 I preferably arrange these tubes so that they extend through the upper part of the wall, providing the buck stay plate with notches h^7 to receive the tubes. These tubes are therefore steadied and held in position by the wall and I sometimes add a further refractory deflector in the form of an inclined front arch M which I arrange against the rear face of the upper part of the wall forming this arch of bricks m^1 , these bricks being of a suitable length so they extend between and are supported upon the tubes. The bricks are preferably arranged in rows across the firebox and in rows longitudinally in the firebox. This arch extends from the wall toward the rear end of the firebox, but I am careful to maintain between the rear end of the wall and the flue sheet a space m^2 sufficient to permit the gases of combustion to flow upward and forward 80 in the firebox from the main combustion chamber a^9 to the auxiliary combustion chamber a^8 . This arch serves to cause the products of combustion to flow rearwardly in the firebox whereby they are caused to contact with substantially the whole interior surface of the firebox and particularly with the crown sheet through which they can efficiently deliver heat to the boiler water. Not only does the arch serve to 90 cause this distribution of the gases in the firebox but it also serves to cause the thorough intermingling and intermixing of the gases, and particularly the intermixing of the air discharged into the firebox 100 through the air inlet passages a^6 with the burning gases, whereby substantially complete combustion is insured.

105 In order that the more centrally located tubes F will not encroach too closely upon the lower edge a^8 of the firebox I depress the forward end of the firebox in its middle portion as shown in Fig. 3 at a^{13} , dropping it downward at this point considerably below the tops of the drivers and thus providing sufficient space a^{14} below the forward ends of the central tubes F to prevent the entrance into the tubes of the mud or sediment which collects within the water leg of the boiler upon the foundation ring or mud-ring.

110 As described, the firebox may be said to be closed at its bottom by two planes inclined longitudinally with relation to each other, their meeting edges being considerably lower than their opposite ends, and the firebox being equipped adjacent to the meeting edges of these planes with a transverse refractory wall which divides the firebox into 115 two portions. In other words the side walls 120

of the firebox are V-shaped in side elevation, the point of the V being located at the lower part of the transverse refractory wall.

As many modifications of my invention 5 will readily suggest themselves to one skilled in the art I do not limit or confine my invention to the specific structures herein shown and described.

I claim:

10 1. In a locomotive the combination with the rear drivers, of a fire box the forward end of which is positioned above the drivers, the lower side edges of the fire box being inclined downwardly from the forward end 15 to a point spaced therefrom, a cross wall rising within the fire box at this point, a normally tight closure for the space between the wall and the front end of the fire box, and a grate closing the lower part of the 20 fire box between the wall and the rear end of the fire box, substantially as and for the purpose described.

2. In a locomotive the combination with the rear drivers, of a fire box the forward 25 end of which is positioned above the drivers, the lower side edges of the fire box being inclined downwardly from the forward end to a point spaced therefrom, a cross wall rising within the fire box at this point, an up- 30 wardly inclined substantially tight closure for the space between the wall and the front end of the fire box and a grate closing the lower part of the fire box between the wall and the rear end of the fire box, sub- 35 stantially as and for the purpose described.

3. In a locomotive the combination with the rear driving wheels, of a fire box the forward end of which extends over the drivers, the rear end of the fire box being 40 substantially on a level with the forward end thereof, the lower end of the fire box

being formed on oppositely downwardly inclined planes meeting upon a line spaced from the forward end, a cross wall rising within the fire box from this line, a grate 45 extending upwardly and rearwardly from the wall to the rear end of the fire box, and a substantially tight closure extending upwardly and forwardly from the wall to the forward end of the fire box substantially as 50 and for the purpose described.

4. In a locomotive the combination with the rear driving wheels, of a fire box the forward end of which extends over the drivers, the rear end of the fire box being substantially on a level with the forward end thereof, the lower end of the fire box being formed on oppositely downwardly inclined planes which meet upon a line between the forward end and the middle thereof, a cross 55 wall rising within the fire box from this line a grate extending upwardly and rearwardly from the wall to the rear end of the fire box, and a substantially tight closure extending upwardly and forwardly from the wall to 60 the forward end of the fire box substantially as and for the purpose described.

5. A locomotive boiler firebox having a rectangular mud ring the sides of which are bent downwardly intermediate the front and 70 rear ends of the mud ring, in combination with a cross wall erected in said firebox at the point marked by the bends of said mud ring.

In testimony whereof, I have hereunto set 75 my hand, this 27th day of June, 1913, in the presence of two subscribing witnesses.

FREDERICK F. GAINES.
